UNITED STATES PATENT OFFICE.

ADALBERT FLEISCHMANN, OF FRANKFORT-ON-THE-MAIN, GERMANY, AS-SIGNOR TO THE FIRM OF VOLT-AMPÈRE-GESELLSCHAFT, FLEISCHMANN & CO., OF FRANKFORT-ON-THE-MAIN, GERMANY.

SPEEDOMETER.

No. 846,296.

Specification of Letters Patent.

Patented March 5, 1907.

Application filed May 11, 1906. Serial No. 316,293.

To all whom it may concern:

Be it known that I, ADALBERT FLEISCHMANN, residing at Frankfort-on-the-Main, Kingdom of Prussia, Germany, have invented new and useful Improvements in Speedometers, of which the following is a specification.

This invention relates to a speedometer specially suitable for motor-cars wherein the speed is indicated—for instance, as expressed by the number of revolutions of a revolving shaft—by means of a pointer rigidly connected to a disk which is rotated proportionally to the revolving shaft, this result being brought about by causing pieces of iron which are fixed to the latter to be rotated in front of or between the poles of permanent magnets, whereby rotating or pulsating magnetic fields are produced in the latter, said fields producing eddy-currents in suitably arranged metallic disks of non-magnetic material.

The instrument is illustrated in the accompanying drawings, wherein—

Figure 1 is a diametrical section of one constructional form thereof, and Fig. 2 is a horizontal section on the line A A of Fig. 1. Fig. 3 is a similar section to Fig. 1 of a second constructional form, and Fig. 4 is a horizontal section on the line B B of Fig. 3.

Referring to the figures, *a* is a casing of the speedometer. *b* are permanent steel magnets arranged in the casing with their poles N S directed inward toward the center of the casing and leaving a central vacant space. In this space, at the center of the speedometer, a shaft *c* is mounted in a bearing *d*, which is fixed, by means of screws or other suitable means, to a disk *e*, that is provided with a central circular aperture *f*. To the lower end of the shaft *c* is fixed a horizontal disk *g*, of copper, the periphery of which extends under the poles N S of the magnets *b*.

To the upper end of the shaft *c* is fixed a pointer *h*, which is arranged to move over a scale designed to indicate the speed in revolutions or kilometers per unit of time. A spiral spring *i* tends to return the pointer to its zero position and brings it back to such position when the apparatus is inactive.

A second disk *k*, of non-magnetic material, is located below the copper disk *g* and ar-

ranged parallel thereto. The disk *k* is fixed to a revolving shaft *l* and carries below the magnet-poles a number of arc-shaped pieces of iron *m*, that are spaced apart from one another, said disk *k* and the arc-shaped pieces of iron *m* projecting beyond the edge or periphery of the copper disk *g*, so that said iron pieces *m* are entirely inclosed by the magnetic lines of force. The shaft *l* is mounted in the usual manner by means of a ball-bearing *n*, so as to be capable of revolving in an extension of the casing *a*.

In the constructional form of the speedometer shown in Figs. 3 and 4 the bearing *d* for the shaft *c* is adjustably mounted on the disk *e*, so that the plate *k*, composed of non-magnetic material, which carries the pieces of iron *m*, can be vertically adjusted for the purpose of regulating the degree of sensibility of the speedometer in a simple and rapid manner. For this purpose the support *d*, in which is mounted the shaft *c*, which carries the copper disk *g*, is arranged to be movable in a vertical extension, which is connected with the disk *e* by means of guide-slots *n'* and screws *o* and is adapted to be adjusted and set at the requisite vertical height by means of a screw *p*, that can be rotated from the outside.

The plate *k*, of non-magnetic material, which carries the iron pieces *m*, is fixed to the shaft *l*, which rotates in a ball-bearing. (Not shown in Fig. 3). The shaft *l* cannot move in the direction of its length; but to enable such a movement to take place it is mounted in an outwardly-screw-threaded sleeve or socket *q*, which is vertically adjustable in an internally-screw-threaded extension *r* of the casing *a*. It is held in its adjusted position by means of a lock-nut *s*.

The manner of operation of the described speedometer and revolution-counter is as follows: By the rotation of the shaft *l* with the disk *k* and the pieces of iron *m* the latter attract the magnetic fields with them in their direction of rotation, and also they short-circuit the magnetic fields alternately. The iron pieces *m* thus produce a continuous pulsating and traveling of the magnetic fields in the same manner as in a rotary-current motor. The pulsating and traveling magnetic fields produce in the copper disk eddy-cur-

rents by which the copper disk is caused to rotate in the direction of the traveling magnetic fields.

What I claim as new and of my invention, and desire to secure by Letters Patent, is—

1. A speedometer, comprising a stationary, permanent magnet, a rotary plate adjacent to said magnet, one or more armature-pieces on said plate, a non-magnetic metal disk interposed between the magnet and the armature, the latter projecting beyond said disk so as to be entirely inclosed by the magnetic lines of force, a spring having a tendency to turn the said element in the opposite direction to the action of the eddy-currents induced by the rotation of the armature, and an indicator for indicating the deflection of said disk from its normal position.
2. A speedometer, comprising a stationary, permanent magnet, a rotary plate located adjacent to said magnet and means for adjusting said plate toward and from the said magnet, one or more armature-pieces on said plate, a non-magnetic metal disk interposed between the magnet and the armature, said armature-pieces projecting beyond the edge of said disk so as to be entirely inclosed

by the magnetic lines of force, means for adjusting said disk toward and from the armature, a spring having a tendency to return said disk to its normal position, and an indicator for indicating the deflection of said disk from its normal position.

3. A speedometer, comprising a stationary, permanent magnet, a rotary plate adjacent to said magnet, one or more armature-pieces on said plate, a non-magnetic metal disk interposed between the magnet and the armature, said armature-pieces projecting beyond the edge of said disk so as to be entirely inclosed by the lines of magnetic force, means for adjusting said disk toward and from said armature, a spring having a tendency to return said element to its normal position, and an indicator for indicating the deflection of said disk from its normal position.

In testimony that I claim the foregoing as my invention I have signed my name, in presence of two witnesses, this 27th day of April, 1906.

ADALBERT FLEISCHMANN.
